United States Patent Office

Des. 205,993
Patented Oct. 18, 1966

205,993

SKI BOOT

Salvatore Ali, 1021 47th St., Brooklyn, N.Y.

Filed Aug. 23, 1965, Ser. No. 86,686

Term of patent 14 years

(Cl. D7—7)

FIG. 1

FIG. 2

FIG. 3

FIG. 4

FIG. 5

FIG. 6

FIG. 1 is a perspective view of a ski boot embodying my new design, shown with the closure in a partially opened position;

FIG. 2 is a side elevational view from one side thereof, shown with the closure fastened;

FIG. 3 is a front elevational view thereof;

FIG. 4 is a side elevational view;

FIG. 5 is a top plan view thereof; and

FIG. 6 is a rear elevational view.

I claim:

The ornamental design for a ski boot as shown.
